A. SEMENICK

SATCHEL

Filed Feb. 27, 1922

UNITED STATES PATENT OFFICE.

ANTHONY SEMENICK, OF BUFFALO, NEW YORK.

SATCHEL.

Application filed February 27, 1922. Serial No. 539,663.

To all whom it may concern:

Be it known that I, ANTHONY SEMENICK, a citizen of Poland, residing at Buffalo, in the county of Erie and State of New York, 5 have invented certain new and useful Improvements in Satchels, of which the following is a specification.

This invention relates to satchels and has special reference to a satchel of the type 10 used by students in carrying their books and lunches to school, and by workmen and others in carrying tools and lunches.

One important object of the invention is to improve the main construction of devices 15 of this character.

A second important object of the invention is to provide an improved arrangement of partition in satchels of this description the arrangement being such that the partition 20 may be folded out of the way when carrying large books or other bulky articles, the said partition being readily changed from its folded position to an unfolded position so as to divide the satchel into upper and 25 lower compartments, the lower compartment being utilized for books and the like, while the upper compartment may be utilized for lunches.

A third important object of the invention 30 is the provision of an improved closure arrangement for such satchel wherein a flexible closure is used and in which such flexible closure is constantly urged into partial open position by certain spring means of a 35 novel arrangement.

With the above and other objects in view, the invention consists in general of certain novel details of construction and combinations of parts hereinafter fully described, 40 illustrated in the accompanying drawings, and specifically claimed.

In the accompanying drawings, like characters of reference indicate like parts in the several views, and:—

45 Figure 1 is a front elevation of a satchel constructed in accordance with this invention one of the corners being broken away and shown in section the better to disclose the relation of the several parts.

50 Figure 2 is an end elevation of such satchel.

Figure 3 is a vertical section on the line III—III of Figure 1.

Figure 4 is a detail view of a portion of

the interior and the closure showing certain 55 section plate on the backing plate used therewith.

Figure 5 is a detail section on the line V—V of Figure 3.

In the embodiment of the invention as 60 herein illustrated there is provided a satchel having end walls which are preferably formed with a wooden core 10 covered on the outside with leather or other like material such as oil cloth as indicated at 11. A 65 suitable lining 12 covers the inside of these end walls as best seen in Figure 1. These end walls are held at the top in spaced relation by a rod 14 and are shaped to support the satchel cover which preferably consists 70 of an outer layer 15 of the same or similar material to the layer 11, one or more stiffening layers 16 which may be of paste board, thin wood or any other suitable material, and a lining 17 of the same general character as the lining 12. This material is held on to the wooden ends by means of nails 18 passing through binding strips 19. The casing thus formed terminates at the front 75 somewhat below the middle of the height of 80 the box and extends downward around the bottom and up to a point adjacent the top of the box, the ends above this being shaped semi-circularly in end elevation. The layers 85 15, 16, and 17 are continued beyond this to 90 extend above the top of the box and down to the front of the casing which they slightly overlap. At the center of the rear wall of this casing the layers 17, and 16 are separated to form a pocket wherein is mounted 95 certain spring means consisting of one or more plate spring strips 20 held in a suitable casing 21. These strips are so shaped that they tend normally to hold the loose or covering part of the casing raised as shown in Figure 3 to afford access to the interior of 100 the satchel. On the front of the lower part of the casing are mounted hinged straps 22 carrying hooks 23 and provided with suitable openings wherethrough may pass eyes 105 24 mounted on plates 25 secured by rivets 30 to the cover portion of the casing, said cover portion being provided on its under side with washer plates 31 through which said rivets pass. Thus the cover may be locked down 110 on the front of the casing. Connected to each end of the casing is a strap 32 and the free ends of these straps are connected by

suitable means, as by the belt buckle 33. Thus the strap 33 may be adjusted to suit the wearer or user. On each of the ends of the satchel is mounted a ledge strip 34 and between the rear ends of these strips and the rear wall of the satchel is pivoted a shelf member 35 provided with a cover 36 preferably of the lining material. The lining on top of this shelf member extends forwardly 10 over a shelf flap 37 and then passes around the front edge of the said flap and under the bottom layer of lining material on the body 35 as at 38. It is to be noted that this portion 38 is free from the main shelf member 15 so that the shelf flap may be folded back and thus enabling the shelf to be folded up on the dotted line portion shown in Figure 3.

In using the satchel the shelf may be folded into this dotted line position thus 20 affording clear access into the bottom chamber or space in the satchel. Books, tools or the like may then be passed freely into this space after which the shelf may be unfolded to rest on the ledges 34 as shown in full 25 lines in Figure 3. A lunch box or the like may then be placed on the upper shelf in the space above on this shelf. It is to be noted that the action of the spring 20 holds the front of the cover portion of the casing 30 up during the time access is desired to the interior of the satchel. This cover may be then folded down and secured by the hooks 23. Attention is called to the fact that it 35 not necessary at all times to remove the contents of the satchel under the shelf as the shelf flap may be lifted up without moving the shelf body. In this way books can readily be lifted out.

There has thus been provided a simple 40 and efficient device of the kind described and for the purposes specified.

Having thus described the invention, what is claimed as new, is:—

1. In a satchel of the class described, an 45 outer casing having end walls, ledges fixed on the inner faces of said end walls opposite each other, and a shelf hinged to the end walls and resting normally on said ledges and consisting of a main shelf member 50 to which said hinges are attached, and a shelf flap hinged to the front edge of the

main member and foldable over to lie on top of the main member.

2. In a satchel of the class described, an outer casing having end walls, ledges fixed 55 on the inner faces of said end walls opposite each other, and a shelf hinged to the end walls and resting normally on said ledges and consisting of a main shelf member to which said hinges are attached, and a shelf flap hinged to the front edge of the main member and foldable over to lie on top of the main member, said main shelf member being hinged in sufficient spaced relation to the rear wall to permit the flap 60 member to be folded onto the main member and the two to be swung upward and backward to bring the flap flat against said rear wall.

3. In a satchel of the class described, 70 rigid end walls having rounded tops, a casing of flexible material attached to the lower front parts, the bottoms and the backs of end walls below the rounded tops and extending freely from the upper point of 75 attachment at the back, said casing being arranged to fold over the rounded tops to bring the edges of the casing together at the front, and a spring steel strip fixed to the back part of the casing and to the free 80 part thereof, said strip being arranged to urge the free portion to raised position.

4. In a satchel of the class described, rigid end walls having rounded tops, a casing of flexible material attached to the lower 85 front parts, the bottoms and the backs of the end walls below the rounded tops and extending freely from the upper point of attachment at the back, said casing being arranged to fold over the rounded tops to 90 bring the edges of the casing together at the front, said casing consisting of a plurality of layers and having a pocket formed in said layers at the back intermediate the ends, said pocket extending into the free 95 portion of the casing and a strip of spring steel located in said pocket and arranged to urge the front of the free portion to raised position.

In testimony whereof I affix my signature. 100

ANTHONY SEMENICK.
